Primary Examiner — Sandra Snapp*Assistant Examiner* — Molly Loch(74) *Attorney, Agent, or Firm* — Saidman DesignLaw Group, LLC(57) **CLAIM**

The ornamental design for a wristwatch body, as shown and described.

DESCRIPTION

FIG. 1 is a left, rear, and bottom perspective view of a wristwatch body showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings illustrate portions of the wristwatch body that form no part of the claimed design.
